REEL FOR EXTENSIBLE ANTENNAS

Robert J. Nagel, Lake Placid, Fla., assignor of
one-half to Richard Archbold, Lake Placid, Fla.

Application July 15, 1948, Serial No. 38,931

3 Claims. (Cl. 242—54)

1

This invention relates to new and useful improvements and structural refinements in extensible antennae for vehicles such as automobiles, trucks and the like, and the principal object of the invention is to facilitate extension and retraction of such antennae by remote control, that is, from the "driver's seat," without the necessity of the driver leaving his seat for the purpose of extending or retracting the antenna unit.

This object is achieved by the provision of a control wherein a flexible shaft, connected to one of the antenna sections, is windable upon a spirally grooved disc driven by a reversible electric motor, so that by rotating the disc in one direction or the other, the antenna may be retracted or extended, as desired.

An important feature of the invention resides in the provision of limit switches, which, responding to the movement of the antenna, are effectively employed for stopping the actuating motor when the antenna is fully retracted or extended.

An important advantage of the invention lies in its simplicity of construction, convenience in operation, and in its adaptability to vehicles of various sizes and types.

With the above more important objects and features in view, and such other objects and features as may become apparent as this specification proceeds, the invention consists essentially of the arrangement and construction of parts as illustrated in the accompanying drawings, in which:

Figure 1 is an elevational view of the invention;

Figure 2 is a further elevational view, taken substantially in the direction of the arrow 2 in Figure 1;

Figure 3 is a cross sectional view, taken substantially in the plane of the line 3—3 in Figure 2;

Figure 4 is a cross sectional view, taken substantially in the plane of the line 4—4 in Figure 2;

Figure 5 is a fragmentary perspective view showing the mounting of the antenna;

Figure 6 is a cross sectional view, taken substantially in the plane of the line 6—6 in Figure 1;

Figure 7 is a cross sectional view, taken substantially in the plane of the line 7—7 in Figure 1;

Figure 8 is a cross sectional view, taken substantially in the plane of the line 8—8 in Figure 2;

Figure 9 is a fragmentary cross sectional view of a tubular guide and shaft used in the invention;

Figure 10 is a perspective view of a traveller used therein, and;

Figure 11 is a wiring diagram of the electrical components of the invention.

2

Like characters of reference are employed to designate like parts in the specification and throughout the several views.

Referring now to the accompanying drawings in detail, the general reference character 20 designates an extensible vehicle antenna of more-or-less conventional type, the same embodying in its construction a plurality of telescoped, slidable sections, 22, 24, 26, as will be clearly apparent.

10 The uppermost section 22 terminates in a tip 28, and it is to be understood that the telescoped portions of the sections are provided with slidable bushings 30 (see Figures 6 and 7), whereby the entire antenna is prevented from undue bending or flexing at the connection of the sections.

The essence of novelty in the invention resides in the provision of an extending and retracting mechanism or control for the antenna 20, this being designated by the general reference character 32 and including in its construction a substantially circular housing 34 provided with a removable cover 36 which is attached thereto by suitable screws 38, this cover preferably being disposed at one side of the housing, while the remaining side of the housing is formed with a reinforcing rib 40 which extends beyond the periphery of the housing and terminates in a split clamp 42 in which the lower portion of the lowermost antenna section 26 may be firmly and securely clamped by means of suitable clamping screws 44, and will be clearly apparent.

It is to be noted that the arrangement of the rib 40 and clamp 42 is such that the longitudinal axis of the antenna 20 is disposed obliquely with respect to the plane in which the housing 34 is disposed, and it will be also observed that the lower end of the antenna section 26 is provided with an insert 46 formed with a substantially frusto-conical bore 48. (See Figure 6.)

40 The insert 46 is secured in position by a suitable set screw 50, and a clamp 52 is also mounted on the lower end of the antenna section 26 by means of a clamping screw 54, substantially as shown.

45 The configuration of the clamp 52 will be clearly apparent from the accompanying drawings, and a similar clamp 56 is swingably connected to the clamp 52 as at 58, as is best shown in Figure 5.

50 The clamp 56 is secured in position by means of a clamping screw 60 on the upper end portion of a tubular guide 62, the purpose of which will be hereinafter more fully described.

A shaft 64 is rotatably mounted in the housing 34 by means of suitable anti-friction bearings.

66 (see Figures 3 and 4), and a disc 68, disposed in the housing 34, is secured to the shaft 64, substantially as shown.

The disc 68 is provided on one side thereof with a continuous, spiral groove 70, and a flexible element, such as a shaft 72, is windable in this groove. One end, that is, the inner end of this shaft is secured in the groove 70 adjacent the shaft 64 as indicated at 74 (see Figure 3), and the shaft 72 after leaving the groove 70, passes through the aforementioned tubular guide 62 and through the substantially frusto-conical passage 48 of the insert 46, and extends upwardly through the various sections of the antenna 20, whereupon its outer end portion is rigidly secured to the antenna tip 28. The aforementioned cover 36 of the housing 34 may be fabricated from several, separately removable sections, or alternatively, the cover may be provided with a suitable opening 76, whereby the lower portion of the guide 62 may enter the housing for the purpose of receiving the shaft 72. Moreover, the lower end of the guide 62 is formed with a laterally projecting detent 79, which is intended to ride in the groove 70 when the disc 68 is rotated. It is to be also noted that the upper and lower edges of the opening 76 in the cover 36 are complementarily bevelled as shown by the phantom lines in Figure 1, so that they are disposed in substantially parallel planes to the longitudinal axis of the antenna 20, as will be clearly apparent. In this manner, the entry of the guide 62 into the housing 34 is facilitated, without the guide being obstructed by the edges of the opening 76 in the cover.

It will be apparent from the foregoing that rotation of the disc 68 in one direction or the other will wind or unwind the shaft 72, thereby extending or retracting the antenna 26. Moreover the guide 62, together with the detent 79 engaging the groove 70, will assure that undue binding or twisting of the shaft does not occur between the time it leaves the groove 70 and enters the insert 46, and vice versa, as will be clearly understood. If desired, suitable compression springs 78, 80 may be provided within the antenna 20 between its adjacent sections 22, 24, and 24, 26, so as to normally urge the antenna to its extended position and thereby assist in overcoming the effect of gravity when the antenna is being extended by rotation of the disc 68.

Rotation of the disc 68 is effected in the following manner:

A worm gear 82 is secured to the aforementioned shaft 64 and meshes with a worm 84, the latter being provided upon a further shaft 86 which is journalled in suitable bearings 88, 90, 92, secured to the aforementioned cover 36. A reversible electric motor 94, provided with a right angled gear reduction drive 96, is mounted upon the cover 36 by means of a suitable bracket 98, the motor 94 being operatively connected to the shaft 86 through the medium of the drive 96, as will be clearly apparent.

The shaft 86 is also provided with a diametrically reduced, screw threaded portion 100 which is disposed between the bearings 88, 90 as shown in Figure 2, and a traveller 102, provided with an internally screw threaded boss 104, is longitudinally shiftable on the shaft portion 100, as will be clearly apparent. The traveller 102 is selectively engageable at the opposite ends of its travel with normally open "limit" switches 106 and 108 provided in the bearings 88, 90, so that as the shaft portion 100 is rotated in one direc-

tion or the other by means of the motor 94, the antenna 20 is extended or retracted as has been already described, and at the same time, the traveller 102 comes in contact with one of the switches 106, 108 when the antenna reaches its fully extended or retracted position. That switch, being opened by the traveller 102, opens the electric circuit to the motor 94, and thereby prevents further extension or retraction of the antenna.

A suitable double pole, three-position switch 110 is in series circuit with the motor 94 and the limit switches 106, 108, the latter, in turn, being electrically connected to a storage battery 112 of the vehicle on which the invention is used. Accordingly, matters are so arranged that by moving the switch 110 in one direction or the other, the reversible motor 94 may be energized so as to extend or retract the antenna, as will be clearly apparent.

Finally, it is to be noted that the pivoted connection 58 of the guide 62 will effectively permit the guide to follow the continuous, spiral groove 70 in the disc 68 while the shaft 72 is being wound or unwound.

If desired, spaced parallel guide rods 114 may extend between the bearings 88, 90, passing slidably through suitable apertures 116 formed in the traveller 102, whereby movement of the traveller will be effectively guided and rotation thereof with respect to the shaft portion 100 prevented.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction and arrangement of parts may be resorted to without departing from the spirit and scope of the invention as claimed.

Having described the invention, what is claimed as new is:

1. In association with an extensible antenna, an extending and retracting mechanism comprising a disc-shaped housing mounted obliquely adjacent one end of said antenna and having a side provided with an opening, a disc rotatable in said housing and formed in one side thereof with a continuous spiral groove, a tubular guide pivoted at one end thereof to said antenna and having a free end portion extending in said housing through said opening, a detent provided at the free end portion of said guide and engaging said groove, a flexible element having one end thereof anchored to said disc and its remaining end secured to said antenna, said element passing through said guide and being windable in said groove, means for rotating said disc, said means including a reversible electric motor operatively connected to said disc.

2. In association with an extensible antenna, an extending and retracting mechanism comprising a disc-shaped housing mounted obliquely adjacent one end of said antenna and having a side provided with an opening, a disc rotatable in said housing and formed in one side thereof with a continuous spiral groove, a tubular guide pivoted at one end thereof to said antenna and having a free end portion extending in said housing through said opening, a detent provided at the free end portion of said guide and engaging

said groove, a flexible element having one end thereof anchored to said disc and its remaining end secured to said antenna, said element passing through said guide and being windable in said groove, means for rotating said disc, and stop means for limiting the extent of rotation of said disc.

3. In association with an extensible antenna, an extending and retracting mechanism comprising a disc-shaped housing mounted obliquely adjacent one end of said antenna and having a side provided with an opening, a disc rotatable in said housing and formed in one side thereof with a continuous spiral groove, a tubular guide pivoted at one end thereof to said antenna and having a free end portion extending in said housing through said opening, a detent provided at the free end portion of said guide and engaging said groove, a flexible element having one end thereof anchored to said disc and its remaining end secured to said antenna, said element passing through said guide and being windable in said groove, means for rotating said disc, a driven shaft rotatable in said housing and carrying said disc, said means comprising a reversible electric
